UNITED STATES PATENT OFFICE.

CHARLES T. HARKREADER, OF QUINCY, ILLINOIS.

SHANK FOR SHOES.

Application filed August 7, 1928. Serial No. 298,020.

This invention relates to shanks for shoes and more particularly to shanks for use in welt or "McKay" shoes.

An important object of the invention is to provide a shank which will afford at once a rigid support, limiting downward movement of the longitudinal arch of the foot and a flexible and flexing support moving upwardly to engage the foot arch when pressure is applied to the forward end of the arch.

A further object of the invention is to produce a device of this character which may be very readily and cheaply constructed and which may be very readily inserted in the shoe in the construction thereof.

These and other objects I attain by the construction shown in the accompanying drawing, wherein for the purpose of illustration is shown a preferred embodiment of my invention and wherein:

Figure 1 is a side elevation of a shoe shank constructed in accordance with my invention;

Figure 2 is a plan view thereof, a portion of the pad being removed;

Figure 3 is a sectional view through the pad;

Figure 4 is a section on the line 4-4 of Figure 1;

Figure 5 is a section on the line 5-5 of Figure 1;

Figure 6 is a detached plan view of the adjacent ends of the shank sections.

Referring now more particularly to the drawing, the shank 10 in general is arched from end to end and has at its forward end a reflexed curved portion 11 adapted to be positioned beneath the forward end of the arch of the foot. The rear portion of the shank is slightly dipped or concaved in its upper surface, as indicated at 12, to conform to the natural curvature of the heel. This shank is formed in two sections 13 and 14, adjacent ends of which overlap and are provided with oppositely extending notches 15, which open through opposite side edges thereof, so that these overlapped portions may be interdigitated. The portions 16 of these sections lying outwardly of the notches are offset slightly, so that the sections when combined are disposed in alignment with one another. These portions 16 each engage the other section to limit the pivotal movement at the connection thus provided when the shank is in its properly lowered arch position.

It will be obvious that upon the application of pressure to the forward end of the section 14, which is provided with the reflexed curve 11, the camber 17 of this curve will act as a pivot upon which the section 11 may rock, forcing the pivotal connection upwardly so that the contact with the arch of the foot is maintained and the arch is supported. The outer end of the section 14 is preferably widened to form a triangular head 18, which is centrally apertured, as at 19, with a polygonal aperture. A pad, preferably of soft rubber, is provided, consisting of portions adapted to engage opposite faces of the head, indicated at 20, and a portion 21 extending through and fitting the aperture 19. The portions engaging one face of the head are made relatively thin so that they may be readily flexed to admit of their passage through the aperture. The heel portion 13 is provided with openings 22 for the passage of securing elements to secure the same to the heel of the shoe.

It will be obvious that a device of this character may be readily produced by stamping and accordingly may be very cheaply manufactured. Due to its structure, it is easily embodied in the shoe in the manufacture thereof and will materially assist in supporting the arches of the foot when the wearer is standing or walking.

Since the construction hereinbefore set forth is capable of a certain range of change and modification without materially departing from the spirit of the invention, I do not limit myself to such specific structure except as hereinafter claimed.

I claim:

1. A shoe shank comprising a metallic arch having at its forward end a reflexed curve adapted to underlie the forward end of the longitudinal arch, said metallic arch being formed in pivotally connected sections the pivotal connection of which extends transversely of the center of the arch and limits downward movement of the sections, the section having the reflexed curve being broadened at its end and provided with a polygonal aperture, and a cushioning pad comprising portions adapted to abut opposite faces of said broadened portion and a connection between the first mentioned portions extending through and fitting said aperture.

2. A shoe shank comprising a metallic arch support having at its forward end a reflexed curve adapted to underlie the forward end of

the longitudinal arch of the foot, said arch support being formed in two sections having a combined length greater than the length of the arch support, adjacent ends of the sections having in opposite side edges thereof and at points slightly spaced from such ends notches, the notch of each section receiving the portion of the other section transversely aligning with the notch thereby permitting interdigititation of the sections while in alignment with one another, said end of each sec-

tion being slightly offset to permit the sections to be disposed in alignment with one another when the arch is in its normal position, said end portion limiting downward movement of the sections in the normal position of the arch while permitting upward movement thereof to increase the camber of the arch support. 15

In testimony whereof I hereunto affix my 20
signature.

CHARLES T. HARKREADER.
